(57) **CLAIM**

The ornamental design for a mobile phone case, as shown and described.

DESCRIPTION

FIG. 1 is a perspective view of a mobile phone case, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective thereof, with the phone case shown in condition of use; and,

FIG. 9 is an exploded perspective view thereof.

The broken lines depicting a mobile phone, in FIGS. 8 and 9, represent environmental subject matter which form no part of the claimed design. The broken lines on the interior of the case in FIG. 3 depict portions of the mobile phone case which form no part of the claimed design.
